UNITED STATES PATENT OFFICE.

GEORGE J. HANKINS, OF PRAIRIE, MISSISSIPPI.

ASH-BOX.

1,114,470.

Specification of Letters Patent.

Patented Oct. 20, 1914.

Application filed January 17, 1914. Serial No. 812,827.

To all whom it may concern:

Be it known that I, GEORGE J. HANKINS, a citizen of the United States, residing at Prairie, in the county of Monroe and State 5 of Mississippi, have invented certain new and useful Improvements in Ash-Boxes, of which the following is a specification, reference being had to the accompanying drawings.

10 This invention comprehends certain new and useful improvements in ash boxes and has for its primary object to provide an ash box which may be employed in connection with a hearth or open fireplace and which 15 will be highly efficient as well as extremely simple and cheap in construction.

Another object is to provide a device of this character which will be composed of the minimum number of parts and which will 20 be of such construction that it may be secured in the floor of the fireplace to receive the ashes and conduct the same to receptacles positioned beneath said floor.

A further object is to provide a device of 25 this character including means which may be operated from within the house to force the ashes from the ash box to the receptacles positioned therebeneath.

A further object is to generally improve 30 and simplify the construction and operation of devices of this character and increase the efficiency of the same, without materially increasing the cost of manufacture thereof.

With the above and other objects in view, 35 my invention consists in certain novel constructions, combinations, and arrangements of parts to be hereinafter more fully described, claimed, and illustrated in the accompanying drawings, in which,

40 Figure 1 is a vertical sectional view of my complete device in use; Fig. 2 is a plan view of the ash box, partly in section, with the plunger and plunger head in position; Fig. 3 is a vertical longitudinal section through 45 the ash box; Fig. 4 is a transverse sectional view on the line 4—4 of Fig. 3; Fig. 5 is an end elevational view; Fig. 6 is a transverse sectional view on the line 6—6 of Fig. 2; Fig. 7 is a fragmentary detail view of a portion 50 of the operating lever, showing in section, a portion of the wall through which the lever extends; and Fig. 8 is a reduced perspective view of the removable cover for the ash box.

55 Referring more specifically to the drawings in which similar reference characters

designate corresponding parts throughout the several views, 1 designates an open fireplace, the floor 2 of which is provided with a rectangular opening 3, in which I have positioned my improved ash box 4. The ash box 4 is of rectangular form and has its opposite ends closed by the removable heads 5. The ash box 4 is also provided with a transversely slotted removable cover 6 and is positioned in the opening 3 so that the top or upper face of the ash box is flush with the upper face of the floor 2, whereby the ashes will drop into the box through the slots 7 in the removable cover 6.

Longitudinal movement of the cover 6 is prevented by the opposite ends 8 of the box 4 while transverse movement of said cover is prevented by the longitudinal ribs 9 formed on the under face of said cover near 75 the opposite edges thereof and adapted for engagement upon the seats 10 formed in the box 4 along the upper longitudinal edges thereof by decreasing the thickness of the sides of the box along said upper edges 80 thereof.

In the bottom of the box 4 adjacent its opposite ends, I have provided outlet openings 11 with depending flanges 12 around the same and beneath which may be positioned ash cans 13 or other suitable receptacles for receiving the contents of the ash box 4. In order to force the contents of the box 4 through the outlet openings 11, I have provided the plunger 14 slidably engaged 85 through one of the heads 5 and having a plunger head 15 mounted upon its inner end. In the outer end of the plunger 14, I have mounted a transverse pin 16 engaged in a longitudinal elongated slot 17 in the 90 lower end of the operating lever 18. The operating lever 18 extends vertically in the wall of the building to one side of the fireplace and has its upper end bent horizontally and engaged through a suitable sleeve 100 19 in an opening 20 in the wall, said end projecting into the room within which the fireplace is positioned and being bent to form a handle 21 by means of which the operating lever may be rocked upon its horizontal 105 portion to reciprocate the plunger 14 and cause the plunger head 15 to force the contents of the ash box 4 through the outlet openings 11 at the opposite ends of the box 4, whenever it is necessary to clean out said 110 ash box 4.

It will be understood that the interior of

the ash box 4 is preferably concaved, in order that the contents of the same may be more readily forced toward the opposite ends thereof, by the plunger head 15. It will also be understood that the opposite ends of the ash box 4 are suitably secured to the joist 22 beneath the opposite ends of the fireplace 1 to securely support the ash box 4 in position.

10 While I have shown the preferred embodiment of my invention, it will be understood that minor changes in the details of construction and arrangement of parts may be made within the scope of the appended 15 claim without departing from the spirit of my invention or sacrificing any of the advantages of the same.

What is claimed is:—

20 A device of the class described comprising the combination with a fireplace, of an

ash box mounted in the floor of said fireplace and having a slotted cover through which ashes from the fireplace may pass into the box, said box having a discharge opening in each end thereof, a plunger rod disposed through one end of said box, a plunger connected to the inner end of said rod, said plunger being normally disposed centrally of the box, and means connected with the outer end of said plunger to reciprocate 25 the same within said box whereby the ashes may be discharged from the box through the openings in the opposite ends thereof.

In testimony whereof I hereunto affix my signature in the presence of two witnesses. 35

GEORGE J. HANKINS.
